CLAIM

The ornamental design for an outdoor gas griddle, as shown and described.

DESCRIPTION

FIG. 1 is an upper right perspective view of a outdoor gas griddle showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the outdoor gas griddle and form no part of the claimed design.

1 Claim, 6 Drawing Sheets
